(57) **CLAIM**

The ornamental design for electrical connector tab, as shown and described.

DESCRIPTION

FIG. 1 is a top perspective view of an electrical connector tab, showing our new design;

FIG. 2 is a top plan view of the electrical connector tab;

FIG. 3 is a right side elevation view of the electrical connector tab;

FIG. 4 is a bottom plan view of the electrical connector tab;

FIG. 5 is a left side elevation view of the electrical connector tab;

FIG. 6 is a rear elevation view of the electrical connector tab; and,

FIG. 7 is a front elevation view of the electrical connector tab. The unshaded surface inside the broken lines and surrounding the claimed edges forms no part of the claimed design. The claim is directed to the solid line edges only.
